(57) **CLAIM**

The ornamental design for a biological fluid collection device, as shown and described.

DESCRIPTION

FIG. 1 is a perspective view of a biological fluid collection device showing my new design;
 FIG. 2 is a right side elevational view thereof, shown in separated condition;
 FIG. 3 is a front elevational view thereof, as seen in FIG. 1;
 FIG. 4 is a rear elevational view thereof;
 FIG. 5 is a top plan view thereof;
 FIG. 6 is a left side elevational view thereof;
 FIG. 7 is a right side elevational view thereof;
 FIG. 8 is a bottom plan view thereof;
 FIG. 9 is a perspective view of the funnel portion of the biological fluid collection device;
 FIG. 10 is a front elevational view thereof;
 FIG. 11 is a rear elevational view thereof;
 FIG. 12 is a right side elevational view thereof;
 FIG. 13 is a top plan view thereof; and,
 FIG. 14 is a bottom plan view thereof.
